DESIGN FOR A BEVERAGE DISPENSING FAUCET

Frederick C. Picut, Newark, N. J.

Application October 1, 1938, Serial No. 80,174

Term of patent 14 years

To all whom it may concern:

Be it known that I, Frederick C. Picut, a citizen of the United States, residing at Newark, county of Essex, and State of New Jersey, have invented a new, original, and ornamental Design for Beverage Dispensing Faucets, of which the following is a specification, reference being had to the accompanying drawing, forming a part thereof.

Figure 1 is a perspective view of the faucet showing my new design.

Figure 2 is a side elevation of the faucet.
Figure 3 is a side elevation of the faucet, showing the opposite side of the view in Figure 2.

Figure 4 is a top plan view of the faucet.
Figure 5 is a bottom plan view of the faucet.
I claim:
The ornamental design for a beverage dispensing faucet, as shown.

FREDERICK C. PICUT.
